UNITED STATES PATENT OFFICE.

CLIFFORD W. HOPKINS, OF MONTCLAIR, NEW JERSEY, ASSIGNOR TO BERNARD RICE'S SONS, A FIRM COMPOSED OF LOUIS W. RICE AND JACQUES B. RICE, OF NEW YORK, N. Y.

DESIGN FOR A MATCH AND CIGARETTE HOLDER.

43,802.

Specification for Design.

Patented Apr. 1, 1913.

Application filed January 11, 1913. Serial No. 741,589. Term of patent 7 years.

To all whom it may concern:

Be it known that I, CLIFFORD W. HOPKINS, a citizen of the United States of America, residing at Montclair, in the county of Essex and State of New Jersey, have invented a new, original, and ornamental Design for Match and Cigarette Holders, of which the following is a specification, reference being had to the accompanying drawing, forming part thereof.

The drawing shows a perspective view of my match and cigarette holder, showing my new design.

I claim:

The ornamental design for a match and cigarette holder, as shown.

CLIFFORD W. HOPKINS.

Witnesses:

PAUL GOEPEL,

JOHN MURTAGH.
